Primary Examiner — Richard Edgar
Assistant Examiner — Nader Abadir(57) **CLAIM**

The ornamental design for a portable barbecue grill, as shown and described.

DESCRIPTION

FIG. 1 is a first perspective view of a portable barbecue grill showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the selected portion 9 in FIG. 1;

FIG. 10 is an enlarged view of the selected portion 10 in FIG. 2; and,

FIG. 11 is an enlarged view of the selected portion 11 in FIG. 2.

The broken lines shown in the drawings depict portions of the portable barbecue grill that form no part of the claimed design.
